ELECTRIC CONDUCTOR

Edwin J. Schneider, Jamaica, and Merritt B. Bratt, Brooklyn, N. Y., assignors, by mesne assignments, to General Cable Corporation, New York, N. Y., a corporation of New Jersey

Application October 12, 1928. Serial No. 311,998

1 Claim. (Cl. 173—264)

This invention relates to electric conductors and particularly to devices of this class employing nonmetallic casings or jackets; and the object of the invention is to provide a conductor 5 of the class described consisting of two electric wires or strands arranged in a single outer jacket, each wire or strand being first enclosed in a body or casing of rubber, then in a braided casing, two other casings being wound upon the braided casing preferably in opposite directions, the latter casings consisting of flat and twisted paper strands wound in multiple; a further object being to provide a conductor of the class described including between the separate conductor elements, filler members, one of which is in the form of a ground wire; a still further object being to provide a conductor wherein the inner braided casings of the separate strands and the outer braided casing enclosing the separate strands are treated to render the same waterproof as well as fire and water proof; and with these and other objects in view, the invention consists in a device of the class and for the purpose specified, which is simple in construction, efficient in use, and which is constructed 25 as hereinafter described and claimed.

The invention is fully disclosed in the following specification, of which the accompanying drawing forms a part, in which the separate parts of our improvement are designated by suitable reference characters, and in which:—

The drawing is a perspective view showing our improved conductor, and indicating the method of arranging the separate casings thereon.

Our improved electric conductor in the construction shown, consists of two wire strands or conductors proper 1, upon each of which is arranged a number of casings, prior to the assembly of both conductors in an outer casing or jacket, and the brief description of one conductor will apply to both.

Arranged directly on the conductor 1 is a body of rubber 2 upon which is arranged a braided casing or jacket 3 and wrapped upon the casing or jacket 3 is another casing 4 consisting of flat paper strips 4a and 4b arranged in parallel relation and spirally wound upon the casing 3 with adjacent edges of said strips abutting.

Another casing 5 is wound directly upon the casing 4 and consists, in the construction shown, of a plurality of similarly formed twisted cord-like paper strands 5a which are wound in multiple, a multiple of six being shown in the drawing. This casing is wound upon the casing 4

spirally in a direction opposite to the winding of the casing 4 as will be apparent.

The two conductors with the casings 3, 4 and 5 thereon are contained within an outer braided casing or jacket 6, and in the crevices formed 60 between the separate conductors within the casing 6 are filler members 7 and 8, one of which may be of cord, twisted paper or the like, and the other is preferably in the form of a wire strand which is utilized as a ground wire in the 65 use of our improved conductor.

In the manufacture of the conductor, it is preferred that the separate casings or windings are treated with a waterproof compound which has a sufficient quantity of wax to insure against 70 adhesion between the separate parts and this compound will include a fireproofing element as applied to the outer casing 6 and the compound on the inner casing 3 may be of a fireproof type or a combination fire and waterproof type. 75

With the structure herein disclosed, it will be apparent that a strong and durable as well as flexible construction is provided for the conductors 1 in the several casings employed, and one of the distinctive features of the invention 80 resides in providing an inner braided casing 3 arranged directly upon the body of rubber 2, which permits the insertion of the conductor with the body 2 and casing 3 thereon into outlet boxes, fixtures and the like with a greater 85 amount of protection to the conductor, the braided casing serving as a protector and guard for the rubber body, and in opening up the conductor to separate the separate strands and in stripping said strands of the casings 4 and 5, this 90 result is facilitated by employing the multiple wrappings and the free and quick release between the respective casings by virtue of the compound employed.

While we have shown certain specific types 95 of protector casings with a particular arrangement thereof, it will be understood that the invention is not necessarily limited to this specific structure and various other changes in and modifications of the structure herein set out may 100 be made within the scope of the appended claim without departing from the spirit of our invention or sacrificing its advantages.

Having fully described our invention, what we claim as new and desire to secure by Letters 105 Patent, is:

An article of manufacture comprising in combination with a metal electric conductor, a body of insulating material surrounding said conductor, a braided protector covering mounted 110

upon said body, a protector casing consisting of thin, flat paper tape material spirally wound upon said braided covering, another protector casing spirally wound upon said first named

5 casing in a direction opposite to the windings of the first named casing, the second named cas-

ing being composed of twisted paper cords, and the strips of both of said protector casings being wound in multiple with the edges of said strips in the respective casings abutting.

EDWIN J. SCHNEIDER.
